INVENTOR

BY *Vincent J. Evans.*

J. H. McNamee.

WITNESS:

ATTORNEY

UNITED STATES PATENT OFFICE.

VINCENT GRENFELL, OF ALBUQUERQUE, NEW MEXICO, ASSIGNOR TO I. D. LAMBERT, OF DENVER, COLORADO, AND G. W. JOHNSON, OF ALBUQUERQUE, NEW MEXICO.

STAND.

Application filed May 26, 1922. Serial No. 563,906.

To all whom it may concern:

Be it known that I, VINCENT GRENFELL, a citizen of the United States, residing at Albuquerque, in the county of Bernalillo and 5 State of New Mexico, have invented new and useful Improvements in Stands, of which the following is a specification.

This invention relates to display devices, and has for its object the provision of a 10 stand or receptacle for holding vegetables, fruits or other similar perishable goods whereby not only to preserve the goods against the usual deterioration but also to display them attractively whereby to tempt 15 the purchasing public.

An important and more specific object is the provision of a device of this character which includes a glass covered receptacle within which is disposed an inner receptacle 20 within which are placed the fruits or vegetables to be preserved and displayed, the inner receptacle having a permeable covering adapted to be impregnated with a disinfectant of a peculiar kind whereby the vegetables or other articles will be kept fresh 25 for a comparatively long time and be consequently kept salable.

An additional object is the provision of a device of this character which will be 30 simple and inexpensive in manufacture, sanitary and economical in use, durable in service and a general improvement in the art.

With the above and other objects and advantages in view, the invention consists 35 in the details of construction to be hereinafter more fully described and claimed and illustrated in the accompanying drawings in which,

Figure 1 is a perspective view of my de- 40 vice.

Figure 2 is a cross-sectional view.

Figure 3 is a longitudinal sectional view.

Referring more particularly to the drawings I have shown my device as comprising 45 an outer receptacle 10 which is formed as a wire basket of any desired shape but which is here illustrated as being rectangular and as having flaring sides and ends. This basket structure 10 is reinforced by wire 11 and is preferably provided with folding feet 12 whereby it may be supported in an inclined position as illustrated in Figure 50 1. Hinged upon one side of this basket or

receptacle as indicated at 13, is a cover including a frame 14 and a pane of glass 15. 55 The opposite side of the receptacle 10, that is the side opposite the hinges 13 is formed with a bent-out portion 16 through which the user of the device may insert his thumb or a finger whereby to open the cover. It 60 should also be noticed that the device might be supported in inclined position at any desired angle as I do not wish to restrict myself to the specific angle illustrated in the drawings. 65

Disposed within the outer receptacle 10 is an inner receptacle 17 of the same shape but naturally of somewhat smaller dimensions. This inner receptacle 17 is likewise formed as a wire-basket-like structure and 70 is covered with some permeable material, preferably burlap of any desired thickness or any number of plies or layers. This fabric covering is indicated by the numeral 18.

In the use of my device I first remove 75 the inner receptacle 17 and saturate the burlap covering 18 with salt solution, the proportions of course being variable but one pint of salt to 4 gallons of water being usually sufficient. 80

In actual practice I have discovered that one pint of salt in ten gallons of water makes a solution of the proper strength. To this solution is preferably added for instance a tablespoonful of vinegar. After the burlap 85 covering of the inner receptacle is thus saturated, the inner receptacle is placed within the outer receptacle 10 and the vegetables or fruits to be preserved and displayed are placed within the inner receptacle, after 90 which the glass door is closed. By actual experiment I have discovered that when perishable goods are placed within this device they will keep fresh for several days and will be saleable for a much longer time 95 than if exposed to the air in the ordinary way. It will also be observed that the glass door may be easily opened whenever it is desired to remove any of the goods for purposes of sale or for any other reason. 100

From the foregoing description and a study of the drawings it will be apparent that I have thus provided an extremely simple and yet highly efficient device for storing and displaying fruits, vegetables or 105 other perishable goods not only in a very

attractive way but also in such a way as to protect them against heat, dust, flies and to a great extent from decay.

While I have shown and described the 5 preferred embodiment of the invention, it is of course to be readily understood that I reserve the right to make such changes in the form, construction and arrangement of parts as will not depart from the spirit 10 of the invention or the scope of the subjoined claims.

Having thus described my invention I claim:

1. A display device of the character described comprising an outer tray like open topped receptacle of foraminous material provided with longitudinally extending stiffening rods, an inner receptacle of foraminous material fitting loosely within said 20 outer receptacle and having a fabric covering adapted to be saturated with liquid

and a glazed frame hinged upon the outer receptacle for closing the same.

2. A combined fruit and vegetable display device and cooler, comprising an outer tray like receptacle of foraminous material, an inner tray like receptacle removably fitted within the outer one and likewise formed of foraminous material, means for supporting the device in inclined position to display the contents, a fabric covering surrounding the inner receptacle and adapted to be saturated with a liquid whereby the evaporation thereof will exert a refrigerating action on the contents and a glazed door hingedly mounted on the outer tray member and normally enclosing the inner tray member for protecting the contents thereof.

In testimony whereof I affix my signature.

VINCENT GRENFELL.
